(57) **CLAIM**

I claim the ornamental design for a neck cradle, as shown and described.

DESCRIPTION

FIG. 1 is a front isometric view of a neck cradle showing my new design;

FIG. 2 is a back isometric view of a neck cradle showing my new design;

FIG. 3 is a back bottom isometric view of a neck cradle showing my new design;

FIG. 4 is a front bottom isometric view of a neck cradle showing my new design;

FIG. 5 is a front view of a neck cradle showing my new design;

FIG. 6 is a top view of a neck cradle showing my new design;

FIG. 7 is a bottom view of a neck cradle showing my new design;

FIG. 8 is a left side view of a neck cradle showing my new design;

FIG. 9 is a right side view of a neck cradle showing my new design;

FIG. 10 is a front view of a neck cradle in its folded position showing my new design; and,

FIG. 11 is a back view of a neck cradle in its folded position showing my new design.

The broken lines in the drawings depict portions of the neck cradle that form no part of the claimed design.
